UNITED STATES PATENT OFFICE.

FRANK E. SMITH, OF WEBSTER CITY, IOWA.

OFFICE-TICKLER.

SPECIFICATION forming part of Letters Patent No. 737,166, dated August 25, 1903.

Application filed August 8, 1902. Serial No. 118,975. (No model.)

To all whom it may concern:

Be it known that I, FRANK E. SMITH, a citizen of the United States of America, and a resident of Webster City, Hamilton county, 5 Iowa, have invented a new and useful Office-Tickler, of which the following is a specification.

The object of this invention is to provide an improved filler for office-ticklers or office-10 files indexed for reference to future business from day to day.

My invention consists in the construction of a filler for office-ticklers composed of guide-cards indexed to the months and days there-15 of numerically expressed and subguide-cards indexed to the days of the week, the arrangement being such that any visible designation of a week-day will register or indicate with the corresponding numerical designation of 20 the day of the month and the indication of the month in which such day occurs.

My invention consists, further, in the filler for office-ticklers composed of guide-cards indexed to months and the days of the month 25 numerically expressed, said indications appearing on opposite faces and adjacent the long margins of said cards, and subguide-cards indexed to the days of the week and registering with the indications of months and days 30 of the month on the other guide-cards.

My invention consists, further, in the construction, arrangement, and combination of elements hereinafter set forth, pointed out in my claims, and illustrated by the accompanying drawings, in which—

Figure 1 is a perspective illustrating my improved device. Fig. 2 is a face view of one of my new guide-cards. Fig. 3 is a reverse face view of the guide-card shown in Fig. 2.

This invention relates to that type of devices illustrated by Letters Patent of the United States No. 377,335, granted to me January 31, 1888, and in the present drawings I show the same box 10, having a longitudinal 45 partition 11 near its front wall; but any desired form of holder or casing may be employed as is found most convenient for a given line or business.

Guide-cards 12 are provided, in this instance 50 thirteen in number, and preferably are mounted in and longitudinally of the holder. Of course when a holder of different relative di-

mension from that shown is employed the guide-cards would be positioned accordingly, but preferably approximately perpendicular 55 to the bottom of the holder and parallel with the front wall thereof. The guide-cards 12 are provided with indexes 13, 14, 15, and 16, preferably adjacent the long margins of said cards and designating the months and some 60 of the days of said months, as illustrated. The four indexes on each of the guide-cards compass opposite sides of the long margins of said card and each index preferably is subdivided, as shown, into six days of the month. 65 Each index refers to a month different from the month referred to by any other index on the same card—for instance, the index 13 (arranged for the beginning of year 1902) reads “Dec. 30, Dec. 31, Jan. 1, Jan. 2, Jan. 3, Jan. 4;” the index 14 reads “Sept. 29, Sept. 30, Oct. 1, Oct. 2, Oct. 3, Oct. 4;” the index 15 reads “Mar. 31, Apr. 1, Apr. 2, Apr. 3, Apr. 4, Apr. 5;” and the index 16 reads “June 30, July 1, July 2, July 3, July 4, July 5.” 75 The dates representing legal holidays or other days on which business generally is suspended would be printed on the guide-cards in a different-color ink, preferably red, except “Sunday,” which in each instance is 80 omitted as not being a business day.

Subguide-cards 17 are provided and formed with tabs or projections 18 on their upper edges bearing letters indicating a day of the week for each card. Any common and well-known 85 form of notching or tabbing the margins of the subguide-cards 17 may be employed. I prefer to employ the subguide-cards 17 in groups of six, one card in each group indexed to one business day, as shown, and five or more groups of such cards interposed with the main guide-cards 12, one group between two main guide-cards. The indexes of the subguide-cards would read, as shown, “Monday, Tues- 90 day, Wednesday, Thursday, Friday, Saturday,” and correspond with the adjacent visible index of a main guide-card 12. Since a main guide-card 12 is provided for each week, by applying indexes of four business “weeks” on each card and utilizing thirteen 95 cards, and only five groups of subguide-cards 17 are provided, I have arranged a pointer or indicator 19, which may be an ordinary wire paper-fastener, removably and replace-

ably and interchangeably mounted on one or another of the main guide-cards and, as shown, indicating the space into which the front group of subguide-cards are to be put 5 as used.

In practical use, commencing with the cards as illustrated, on Tuesday, December 31, 1901, the front subguide-card indexed "Monday" is removed into the space immediately in front 10 of the pointer 19. Card after card is removed from the front group until Monday, January 6, 1902, and placed in front of the pointer, and on the latter date the front main guide-card 12 is removed and inverted and replaced 15 at the rear of the rearmost main guide-card. Inverting the guide-card brings index 15 into the position formerly occupied by index 13 at the front of the top margin of the card as positioned in the holder and in succession for 20 use when reached by removal of all cards preceding it. The removal of the front main guide-card 12 reveals another group of subguide-cards registering with another set of dates or index on the margin of the second 25 main guide-card.

I gain a material advantage in putting four indexes on each of the main guide-cards and eliminating three-fourths of said guide-cards in respect of my former invention and at the 30 same time combining the months and days

of the month in the indexes. Another material advantage is found in the provision of the subguide-cards indexing the days of the week adjacent the index of the fractional parts of the month.

35

I claim as my invention—

1. A filler for office-ticklers, composed of guide-cards indexed to months and the days of the month numerically expressed, said indications appearing on opposite faces and 40 adjacent the long margins of said cards, and subguide-cards indexed to the days of the week and registering with the indexes of months and days of the month on the first 45 guide-cards.

2. A filler for office-ticklers, composed of guide-cards indexed to months and the days of the month numerically expressed, said indications appearing adjacent all the long 50 margins of said cards, and subguide-cards indexed to the days of the week and registering with the indexes of months and days of the month on the first guide-cards.

45

Signed by me at Des Moines, Iowa, this 21st day of May, 1902.

FRANK E. SMITH.
